DESIGN FOR A CUFF LINK

Charles P. Guerin, New York, N. Y., assignor to David P. Barry Corp., New York, N. Y., a corporation of New York

Application September 16, 1935, Serial No. 58,564

Term of patent 7 years

To all whom it may concern:

Be it known that I, Charles P. Guerin, a citizen of the United States and resident of New York, in the county of New York and State of New York, have invented a new, original, and ornamental Design for Cuff Links, of which the following is a specification, reference being had to the accompanying drawing forming part thereof.

In the drawing:

Fig. 1 is a perspective view of a cuff link showing my new design;

Fig. 2 is a front view thereof, and

Fig. 3 is a side view thereof.

I claim:

The ornamental design for a cuff link substantially as shown.

CHARLES P. GUERIN.
